Primary Examiner — Cynthia M. Chin(74) *Attorney, Agent, or Firm* — Brian G Schlosser; DeLio Peterson & Curcio LLC(57) **CLAIM**

The ornamental design for a “toy building brick”, as shown and described.

DESCRIPTION

FIG. 1 depicts a side perspective view of the “toy building brick” according to my design;

FIG. 2 depicts a right side elevational view of the “toy building brick” shown in FIG. 1;

FIG. 3 depicts a left side elevational view of the “toy building brick” shown in FIG. 1;

FIG. 4 depicts a top plan view of the “toy building brick” shown in FIG. 1;

FIG. 5 depicts a bottom plan view of the “toy building brick” shown in FIG. 1;

FIG. 6 depicts a front elevational view of the “toy building brick” shown in FIG. 1; and,

FIG. 7 depicts a rear elevational view of the “toy building brick” shown in FIG. 1.

The broken lines and the areas within them in FIGS. 1 and 5 depict portions of the “toy building brick” that form no part of the claimed design.
